(57) **CLAIM**

The ornamental design for a HANDLE FOR RETAINING A CLEANING PAD as shown and described.

DESCRIPTION

FIG. 1 is a front, top, right side, isometric view of a HANDLE FOR RETAINING A CLEANING PAD in accordance with my design;

FIG. 2 is a front elevation view of the HANDLE FOR RETAINING A CLEANING PAD, wherein the rear elevation view is a mirror image of the front elevation view;
FIG. 3 is a top plan view of the HANDLE FOR RETAINING A CLEANING PAD;

FIG. 4 is a bottom plan view of the HANDLE FOR RETAINING A CLEANING PAD;

FIG. 5 is a left side elevation view of the HANDLE FOR RETAINING A CLEANING PAD, wherein the right side elevation view is a mirror image of the left side elevation view; and

FIG. 6 is a cross-section through the HANDLE FOR RETAINING A CLEANING PAD looking in the direction of line 6-6 of FIG. 3.

The broken lines shown in the figures are for the purpose of illustrating the portions of the HANDLE FOR RETAINING A CLEANING PAD and form no part of the claimed design. The broken lines showing of the scrub pad are for the purpose of illustrating portions of the environmental structure and form no part of the claimed design.

1 Claim, 5 Drawing Sheets
